UNITED STATES PATENT OFFICE

151,691

DESIGN FOR AN ANIMAL TRAP

Arthur C. Haggstrom, Rockford, Ill., assignor to
Style Line Products Co., Rockford, Ill., a cor-
poration of Illinois

Application July 22, 1946, Serial No. 131,798

Term of patent 14 years

(Cl. D31—4)

To all whom it may concern:

Be it known that I, Arthur C. Haggstrom, a citizen of the United States, residing at Rockford, in the county of Winnebago and State of Illinois, have invented a new, original, and ornamental Design for an Animal Trap, of which the following is a specification, reference being had to the accompanying drawing, forming part thereof.

In the drawing:

Figure 1 is a perspective side view of an animal trap, showing my new design;

Figure 2 is a perspective side view similar to Figure 1 showing the parts in moved position;

Figure 3 is a side elevational view thereof, the opposite side being a mirror image of Figure 3, and

Figure 4 is a top view thereof.

The dominant features of the design are thus shown in full lines.

I claim:

The ornamental design for an animal trap, substantially as shown and described.

ARTHUR C. HAGGSTROM.
